UNITED STATES PATENT OFFICE.

FRANK F. WEAR AND BERNARD M. ELY, OF CINCINNATI, OHIO, ASSIGNEES TO THE
ALVEY-FERGUSON COMPANY, OF OAKLEY, CINCINNATI, OHIO, A CORPORATION
OF OHIO.

DESIGN FOR A DUST AND AIR SEPARATOR.

52,365.

Specification for Design.

Patented Aug. 27, 1918.

Application filed November 14, 1914. Serial No. 872,259. Term of patent 14 years.

To all whom it may concern:

Be it known that we, FRANK F. WEAR and BERNARD M. ELY, both citizens of the United States, residing at Cincinnati, in the county of Hamilton and State of Ohio, have invented a new, original, and ornamental Design for a Dust and Air Separator, of which the following is a specification, reference being had to the accompanying drawing, forming part thereof.

The figure is a side elevation of a dust and air separator showing our new design.

As shown in the drawing, the lower member of the funnel shaped body is made of glass and the upper member of a metal of a different color from the lower member thus giving an artistic and pleasing appearance to the whole.

Copies of this patent may be obtained for five cents each, by addressing the "Commissioner of Patents, Washington, D. C."

Furthermore the fact that the lower member is transparent renders the far side of said member visible when looking through the near side.

We claim:

The ornamental design for a dust and air separator, substantially as shown.

FRANK F. WEAR.
BERNARD M. ELY.
